Patented Dec. 30, 1919.

FIG. 2.

FIG. 3

FIG. 1.

FIG. 4.

Stephen J. Roche, INVENTOR
John W. Treher, ATTORNEY

UNITED STATES PATENT OFFICE.

STEPHEN J. ROCHE, OF CINCINNATI, OHIO.

TOWEL-HOLDING DEVICE.

1,326,691.

Specification of Letters Patent. Patented Dec. 30, 1919.

Application filed April 16, 1918. Serial No. 228,968.

To all whom it may concern:

Be it known that I, STEPHEN J. ROCHE, a citizen of the United States, residing at the city of Cincinnati, in the county of 5 Hamilton and State of Ohio, have invented certain new and useful Improvements in Towel-Holding Devices, of which the following is a specification.

The object of my invention is to provide 10 a cheap, simple and highly efficient towel holding device, belonging to that class of towel holders or towel racks in connection with which a multiplicity of towels are held or carried, so that the user can individually 15 withdraw or unloosen a towel and suspend the same for his own use.

As a rule, the user first washes his hands or face, then rinses the same, and then reaches for a towel; in the towel holders 20 now in use he must reach up or make an extra effort to pull the towel into a usable position and by so doing, the water on the face runs down onto the neck and the water on his hands and wrists runs down his 25 sleeves.

In the towel holder now used the towel must be taken from the top or front and it is inconvenient to handle then; in my device the towels are easily and readily accessible 30 and are taken or pulled down off of the bottom of the pack and can thus be used conveniently and satisfactorily.

The towels can be readily placed in position by the towel deliverer and taken off 35 conveniently and quickly.

The various features of my invention and their advantages will readily become apparent from the following specification.

In the accompanying drawing forming 40 part of this specification:

Figure 1, is a front view in elevation of the device,

Fig. 2, is a top or plan view, the towels being removed,

Fig. 3, is a view of the sleeve with towels strung thereon, partly broken away, and

Fig. 4, is a sectional view on the line 4—4 of Fig. 1.

In the drawings the numeral 1 represents 50 the back or base of the towel holder, which may be made of any contour or size and from any material. Near the middle part of this back 1, I place a platform or shelf 2 having a cut away part 3, in the present 55 instance U shaped; the towels lie on and are supported on this shelf.

Between the top edge of the back 1 and the outer front edge of the shelf 2 I connect a frame work formed of the strips 4 and 5. I may employ any form of frame 60 work between the shelf 2 and the top of the back 1 and either leave it partly open or use a box shaped receptacle or hood to inclose the towels, leaving means at the bottom however, to reach the towels. 65

At the lower extremity of the back 1, I place a foot 6 provided with a hole 7.

A flexible cable; wire, rope, chain, or the like, 8, and a rigid stem 9 joined together at their meeting edges, form the stringer 70 or suspending means for the towels in connection with a sleeve, to be hereafter described. The flexible lower end 8, passes through hole 7 in the foot piece 6 and its extremity is provided with a weight 10, 75 used to keep the stringer in alinement and to keep it in position and for pulling out the stringer to remove the used towels.

At the end of the stem 9 of the stringer I provide a slot 12 and on the back 1, near 80 its top edge I fasten an eye 13 and above this eye on the top edge of the back 1 I place a hinged hasp 14 provided with a slot 15, which slot passes over the eye 13 when the hasp is swung down, enabling the 85 device to be locked by a lock 16.

The towels are temporarily strung upon a hollow sleeve 17 having near the top a flange 18; the towels 30 being strung thereon through medium of holes or edges 19 in 90 said towels. The distributor or deliverer of the towels strings them upon this sleeve and when they are delivered, the rigid part 9 of the stringer is unloosed from the eye and hasp at the top and the sleeve 17 slid over 95 the part 9 and the towels are pushed down onto the shelf 2 lying across the U-shaped cut away part 3; the part 9 is then again connected at the top to eye 13 by means of hasp 14 and locked. 100

When it is desired to use one of the towels 30, the lower one of the pack (shown partly hanging down at the cut away part 3) is pulled downward until it is freed from the shelf 2; it can then be used and when 105 the user is finished, said used towel falls down to the foot piece 6 and hangs there as shown.

By releasing the rigid part 9, the sleeve with the unused towels can be slid off said 110 part 9 and the stringer pulled out through hole 7 of foot piece 6 and removed and then

the parts can again be placed back into normal position and a fresh supply of towels put in position for use, or the towels may be slid up on the stringer and taken off at 5 the top when it is loosened at its upper extremity.

The towel holder is held on the wall or any place desired by eyes 20.

By reason of the stringer being partly 10 flexible and capable of play, the towel in the hands of the user can be manipulated and twisted and swung around, enabling the towel to be used to full advantage.

It will readily become apparent from the 15 above description that I have evolved a unique, useful, highly efficient and sanitary towel holder which will answer the purpose for which it is intended.

While I have described one specific 20 method of carrying my invention into effect, it will readily be apparent that the same can be somewhat modified and changed without departing from the spirit of the

invention and I wish to be understood as claiming that such modifications will still 25 fall within the scope of my invention.

What I claim as new and my invention and desire to secure by Letters Patent is:

In a towel holder of the character described, a base part, a shelf thereon, said 30 shelf provided with a cut away part, a stringer carrying a weight at its lower extremity and attached at the top and bottom of said base part and extending between said points in combination with separate 40 means for carrying the towels, capable of being placed on and off of said stringer, the stringer being removable and being partly rigid and partly flexible.

In testimony whereof I affix my signature 45 in the presence of two witnesses.

STEPHEN J. ROCHE.
